Term of patent 7 years

(Cl. D58—12.6)

FIG. 1

FIG. 3

FIG. 1 is a front elevational view of a rigid box embodying my new design, the rear being substantially the same;

FIG. 2 is a side elevational view thereof, the opposite side being substantially the same; and

FIG. 3 is an end elevational view thereof, the opposite side being substantially the same.

The characteristic features of my design reside in a rigid box having widely spaced dovetail grooves on the front and rear faces and in short dovetail grooves at right angles thereto extending into longitudinal grooves on each side of both top and bottom surfaces all as shown.

I claim:

The ornamental design for a rigid box for packaging materials such as coffee, as shown and described.
